[57] **CLAIM**

The ornamental design for a wrist-watch, as shown and described.

DESCRIPTION

FIG. 1 is a front elevational view of a wrist-watch showing my new design;

FIG. 2 is a rear elevational view thereof;

FIG. 3 is a top plan view thereof;

FIG. 4 is a bottom plan view thereof; and,

FIG. 5 is a left side elevational view thereof as taken from line 5—5 of FIG. 1.

The band is shown broken away for ease of illustration in FIGS. 1-4; and the band has been omitted from FIG. 5.
